UNITED STATES PATENT OFFICE.

ALPHEUS E. ROE, OF SAN FRANCISCO, CALIFORNIA, ASSIGNOR OF ONE-HALF TO JOHN H. BOLLES, OF SAME PLACE.

CABLE-RAILROAD GRIP.

SPECIFICATION forming part of Letters Patent No. 381,032, dated April 10, 1888.

Application filed August 19, 1886. Serial No. 211,342. (No model.)

To all whom it may concern:

Be it known that I, ALPHEUS E. ROE, of the city and county of San Francisco, State of California, have invented an Improvement in Cable-Railway Grips; and I hereby declare the following to be a full, clear, and exact description of the same.

My invention relates to an improved mechanism for connecting railway cars or carriages with an endless traveling cable, which moves in a tube or tunnel beneath the roadway.

It consists of short endless chains passing around rollers which are journaled upon a frame depending from the car, and so placed that one of the chains will stand above and the other below the cable. In combination with these is a mechanism by which the cable is gripped between the chains or released therefrom for the purpose of starting or stopping the car, and a mechanism by which the lower grip may be thrown to one side to release it entirely from the cable.

My invention also consists in certain details of construction, all of which will be more fully explained by reference to the accompanying drawings, in which—

Figure 1 is a side elevation showing my gripping apparatus and the dummy or truck from which it is suspended, also the actuating levers. Fig. 2 is a transverse section of the grip and car. Fig. 3 is a view showing the mechanism by which the grip is caused to act upon the cable. Fig. 4 is a plan view. Figs. 5 and 6 illustrate perspective views of the lower portion of the grip. Fig. 7 is an enlarged view of the grip, showing the manner in which the same is suspended.

A are the rails of a street or other railway. B is the cable which travels in a tube or tunnel situated centrally beneath this roadway, and in the present case it is shown a little to one side of the slot D, through which the frame E passes to support the gripping mechanism, so as to be out of the line of dirt and dust which may fall through the slot D in the roadway.

F are the wheels of the truck from which the gripping mechanism is suspended. The frame E consists of a broad plate, sufficiently

thin to enable it to pass through the slot D,

and its width may be made considerably greater within the tunnel, so that it has chain pulleys or rollers G journaled to it, as shown in Fig. 1. Said frame E consists of two fixed vertical parts and an intermediate sliding part, T, pivotally connected to lever U. One set of these pulleys is situated below the cable B and the other set above it, both sets standing in a plane which will pass through the cable if projected. Around the pulleys short endless chains H pass, these chains being made in short sections jointed at I, so as to be sufficiently flexible to pass around the pulleys G, and having their outer faces grooved or channeled, so as to form shoes which may be compressed upon the cable. The pulleys G of the upper and lower series are set so near together that when the chains H are in place they will travel in contact with the cable, and with sufficient compressing force, so that when the car is stationary the moving cable will cause the chains to travel continually around their respective supporting-pulleys. When it is desired to start the car, it must be done by stopping the traveling chains when their compression upon the cable is sufficient, so that the latter will cause them, the grip-frame, and car to be moved simultaneously.

In order to stop the revolution of these chains, I form a clutch in the following manner: The shaft or axle of one of the pulleys G is continued through the frame E to the opposite side, and has fixed upon it a pulley, which is more plainly shown at J, Fig. 3. Outside of this pulley is a clamping-ring, K, which may be formed of iron, having a wooden lining or shoe which can be compressed upon the rim of the pulley J. One side of this clamping-ring K is open, and its opposite edges are connected with a cam, L, by the movement of which it may be closed to clamp the pulley and prevent its rotation, or by a partial turn of which the pressure of the ring upon the pulley may be relieved. This action is produced by means of a lever-arm, M, and a connecting rod or link, N, which extends upward and connects with the bell-crank hand-lever O, by which the device is operated.

P is the rack by which this lever is held at

any desired point. When the lever O is moved, it communicates its motion through the link N to the lever M, and this actuates the cam L, so as to close the ring K and cause it to compress tightly upon the pulley J. As this pulley is upon the shaft of one of the chain-pulleys G, it will be manifest that when it is prevented from revolving the chain-pulley, and with it the chain, will also be prevented from revolving, which will cause the rope to move the car along the track by reason of the compression of these gripping-chains upon the rope. The length of the chains being considerable, it produces a shoe of greater length than ordinary, which correspondingly increases the frictional surface and enables it to hold the cable firmly without being compressed so severely by the latter, as is the case with ordinary plain shoes or with single plain rollers which have heretofore been used. The pulley J may be gradually stopped in its rotation, and the action of the cable will be as gradually transferred to the car, so that the latter may be started in its movements as slowly as may be desirable, and the strain upon the cable will be greatly reduced. As the cable is placed to one side of the slot, it will be manifest that in single-track railways both the cables going out and returning may be placed within the same tube, and the same grip may be used to carry the car in either direction by simply reversing it upon the truck without the expense of a turn-table or mechanism for turning the car around. This is done by supporting the frame E within the cylinder Q. (See Fig. 7.) This cylinder is fitted to turn freely in a corresponding vertical guide upon the truck or car supporting the grip, and it is only necessary to turn this around when the car has reached the end of its journey and reverse the grip.

In order to release the rope from the grips, the lower portion of the sliding part T of the frame E is hinged, as shown at R in Figs. 2, 5, 45 and 6, so that this portion carrying the lower set of pulleys, G, may be turned about its hinges, so as to allow the cable to drop out between the gripping-chains. This movement of the lower hinged portion of the frame is produced by means of an arm, S, projecting at right angles to it, and the link T, connecting therewith and extending upward to a lateral projection upon the lower end of the fixed parts E.

55 By means of this mechanism the lower part

of the frame E and the pulleys G, with their chain, may be swung to one side, as shown in the dotted lines in Fig. 2, thus entirely releasing the cable. This enables the car to be moved to any point away from the cable, and 60 the grip may be turned around when the end of the track has been reached, so that the car can be returned without its being reversed.

Having thus described my invention, what I claim as new, and desire to secure by Letters 65 Patent, is—

1. A cable-railway grip composed of parallel endless chains passing around pulleys which carry the chains one above and one below the cable and in close contact therewith, 70 in combination with a friction-pulley secured to the shaft of one of the chain-carrying pulleys, and a strap and operating lever or mechanism by which the pulleys and chains are arrested and caused to travel with the cable, 75 substantially as herein described.

2. The parallel endless chains passing around pulleys above and below the traveling cable, which hold the chains constantly in contact with the cable, a wheel or pulley secured to 80 the extension of the shaft of one of the pulleys, and a clamp or mechanism whereby the motion of the pulleys and chains may be arrested, so that the car to which they are attached may be moved with the cable, substantially as 85 herein described.

3. The parallel endless chains passing around pulleys supported upon the grip-frame traveling in contact with the cable, in combination with a vertical cylinder or turn-table upon the 90 car or truck frame and supporting the grip-frame which passes through its center, so that the whole may be reversed without turning the car, substantially as herein described.

4. The grip-frame composed of two sections 95 hinged together, in combination with chain-pulleys attached in series to each of the two sections, and parallel endless chains passing around said pulleys, so as to be compressed upon the cable, or so that the cable may be released therefrom by the movement of the hinged portion, substantially as herein described.

In witness whereof I have hereunto set my hand.

ALPHEUS E. ROE.
